CLAIM

The ornamental design for a focal plate for surveying instrument, as shown and described.

DESCRIPTION

FIG. 1 is a front, bottom, and right side perspective view of a first embodiment of a focal plate for surveying instrument showing my new design;

FIG. 2 is a front view thereof; the rear view being a mirror image thereof;

FIG. 3 is a top view thereof; the bottom view being a mirror image thereof;

FIG. 4 is a right side view thereof; the left side view being a mirror image thereof;

FIG. 5 is a front, bottom, and right side perspective view of a second embodiment of a focal plate for surveying instrument showing my new design;

FIG. 6 is a front view thereof;

FIG. 7 is a rear view thereof;

FIG. 8 is a top view thereof; the bottom view being a mirror image thereof; and,

FIG. 9 is a right side view thereof; the left side view being a mirror image thereof.

In FIGS. 5-7, the numerals depicted with broken lines illustrate portions of the focal plate for surveying instrument that form no part of the claimed design. In FIGS. 5-7, the concentric circles depicted with broken lines illustrate portion of the focal plate for surveying instrument that form part of the claimed design.
